UNITED STATES PATENT OFFICE.

EDWIN J. MORRISON, OF YONKERS, NEW YORK.

PAVEMENT.

1,335,180.

Specification of Letters Patent. Patented Mar. 30, 1920.

Application filed January 15, 1916. Serial No. 72,212.

To all whom it may concern:

Be it known that I, EDWIN J. MORRISON, a citizen of the United States, residing in the city of Yonkers, in the county of Westchester and State of New York, have invented an Improvement in Pavements, of which the following is a specification.

This invention relates to improvements in pavements and more particularly to improvements in block pavements formed of malleable blocks such as are commonly made from crushed stone and asphaltic cement or the like.

Such malleable paving blocks are ordinarily relatively small, rarely exceeding five inches in width, and in any case are of a size which can be readily handled and laid as units of a sectional pavement.

Pavements of this class necessarily present large numbers of joints between the blocks, and it is impossible to avoid some space between adjacent rows of blocks. Because of these joints and the malleable nature of the block composition there commonly develops a tendency of each block being relatively small to move in the direction of traffic, thus dislodging the pavement from its proper position on the road foundation. If each block could only move the small fraction of an inch which separates it from its neighbor no harm would result but in practice the creeping is cumulative so that substantial and deleterious creeping may take place.

It is the purpose of this invention to overcome or mitigate this deleterious creeping and I preferably perform this by providing a block having anchor means partially embedded therein and partially projecting from the bottom of the block to engage the bed on which the block is laid. I have found in practice that for ordinary traffic sufficient anchorage is provided by distributing the anchor blocks among the other or smooth bottomed blocks, either individually or in suitable groups. The percentage of anchor blocks may of course be varied to suit varying conditions of traffic, grade, and the like, each such block, when laid, tending to avoid deleterious action arising from creeping of individual blocks or groups of blocks.

The invention is capable of various embodiments of which one has been selected for purposes of illustration and explanation, and to which reference will be hereinafter made. This particular embodiment of the

invention is shown in the accompanying drawings, wherein—

Figure 1 is a perspective view of a paving block illustrating one embodiment of the invention;

Fig. 2 is a vertical longitudinal section of the block shown in Fig. 1;

Fig. 3 is a cross section of a portion of a roadway showing the paving block of Fig. 1 laid upon the road foundation; and

Fig. 4 is a diagrammatic plan view of a roadway showing possible arrangements of anchor blocks with the usual paving blocks.

Referring to the drawings, a paving block 1, shown as of the compressed asphalt type, is provided with a suitable bed anchoring means, herein shown as a metal strip 2 embedded in the material of the block and extending downwardly from the under side 3 of the block to be adapted to be impressed into and engaged by the foundation of a roadway. Means may be provided to insure a more positive engagement of the anchor member in the block by providing for a positive gripping of the anchor member by the material of the block. In this instance, the said means are herein shown as a series of holes 5 and 5' in the metal strip which, when the strip is forced into the block when it is in a semi-plastic condition, will be filled by the material of the block and thus positively lock the anchor therein.

In order to provide a maximum resistance to forces tending to move the block upon the road foundation, this anchor member may be of approximately oblong shape as herein shown. Transverse bracing means may be provided for the anchor to obviate any tendency of the anchor when under strain to turn over or pull out of the block or out of the road foundation and, by transversely bracing the block and distributing the weight of the load sustained by the block uniformly over a considerable area of the anchor member, the possibility of splitting the block may be minimized. In the present instance, this may be accomplished by the generally oblong shape of the anchor means whose looped ends provide for the transverse bracing and the distribution of weight. Furthermore, it is believed that an embodiment of the invention approximating in structure the particular anchoring means herein shown may be preferable, due to the fact that it is concealed from sight when the

pavement is laid and that its use does not break the continuity of the road surface.

To provide for a possible unequal relative expansion and contraction of the metal of this particular anchoring member and the block, under the action of the varying temperatures to which the anchor block is subjected in manufacture and use, means herein shown as an opening 4 in one end of the looped anchor member may be provided.

To provide a protective coating for the metal member and to provide a means which will form an adhesive to cause the anchor member to adhere more firmly to the block after it has been pressed therein, the anchor member may be coated with an asphaltic or other suitable solution in the form of paint or otherwise. In the event that this coating is to act merely as a protective coating to prevent rust, it may be applied after the member has been attached to the block.

As a convenient mode of manufacturing the blocks of Figs. 1 and 2, which are herein termed "anchor blocks," the usual asphalt block may be placed in a mold, preferably before it has thoroughly cooled and hardened, and the mold may then be tightened about the block to prevent distortion thereof during the succeeding operations. The looped metal strip, which comprises the anchor member in this particular instance, may be placed in an appropriate slot formed in the pressure head of a suitable press and may be held therein by the resiliency of the metal causing the two sides of the anchor member to spring apart, or by other suitable means. When the pressure head is brought down upon the asphalt block, the metal strip may be readily forced into and set therein.

The usual practice in building a roadway which is to be constructed with a relatively yielding wearing surface such as compressed asphalt blocks, is to provide a foundation having a heavy base 7 which may be of any desired material such as concrete and which may have a mortar bed 8 thereon. This mortar bed is preferably laid after the base 7 has been allowed to set or harden, if a concrete base is used. The paving blocks may then, if a mortar bed is used, be laid while the same is still in the plastic condition, and the anchor blocks may be placed thereon in the manner shown in Fig. 3. In this instance, it will appear that the metal strip bed anchor 2 will, as the block is laid, be impressed into the surface layer 8 of the foundation and, upon the hardening of this surface layer, a positive connection will thus be formed between the block and the foundation and any objectionable lateral movement of the block upon the foundation will thereby be effectively prevented.

In laying the anchor blocks upon the plastic surface material of the base, it may

be found desirable to provide a means to allow for the escape of air which might possibly be trapped within the anchor member, and also to provide for the drainage of any excess water from the mortar bed. Such means are herein provided by the opening 4 and the several holes formed in the sheet metal anchor member. In the event that the anchor member is of the generally oblong shape herein shown, and in the absence of such openings as are provided, air might possibly be trapped within the anchoring means if the block were not laid with great care. If air should be so trapped in the space formed within the anchoring means and have no opportunity for escape, the material of mortar bed 8 might be forced down to such an extent that an imperfect engagement of the anchoring member therewith might result. Moreover, this would leave the center of the block practically unsupported. With the construction herein shown, any trapped air or any excess water is allowed to escape and the anchor block will then be firmly seated upon the base while the plastic material of the base will be permitted to close around the anchoring means and to secure the block firmly to the base.

In order to secure a pavement made up of a plurality of paving blocks from objectionable movement upon the road foundation and to prevent creeping thereof, it may not be necessary to provide every paving block with the anchoring means herein described. For purposes of economy, the anchor blocks may be laid throughout the pavement in rows extending partially or entirely across the roadway or they may be interspersed throughout the pavement at irregular intervals, and it is believed that a distinct advantage may result therefrom in that the pavement may thereby be made more yielding and adaptable to the varying conditions of hard usage while the anchor blocks so used are still sufficient to prevent the objectionable creeping of the pavement herein noted. Possible arrangements of anchor blocks in a completed pavement are shown in Fig. 4, wherein the anchor blocks are distinguished from the ordinary blocks by the representation in dotted lines of the anchoring means shown in Fig. 1.

In laying compressed asphalt blocks, the practice sometimes adopted is to lay the blocks over a substantial area and then drive the blocks together laterally upon the road bed to tighten joints therebetween. This having been done, a row or rows of ordinary blocks may be removed and anchor blocks inserted in place thereof, and these anchor blocks, when the plastic sub-surface of the road has hardened, may be sufficiently effective to hold the entire pavement in place and to prevent the objectionable creep-

ing above noted. The frequency of location of the rows or partial rows of anchor blocks will be determined by the traffic conditions upon any particular roadway or street. It 5 may be found desirable to lay the anchor blocks in the first instance without removing any ordinary blocks, and in this event, the tightening of the joints may be effected immediately preceding the placing of the 10 anchor blocks. Furthermore, where no curbing is provided, a row of anchor blocks may be laid along the edge of the roadway, thus forming a secure border and dividing the roadway up into areas bounded by rows 15 of anchor blocks. It may be found desirable to intersperse the anchor blocks at irregular intervals throughout the pavement at the points where the greatest tendency to creep would develop. Such an arrangement is 20 shown in Fig. 4 of the drawings, and it is believed that such an arrangement may be found preferable in allowing a slight relative movement of the respective sections of the roadway which carry the heaviest 25 oppositely moving traffic.

As stated above a further object of the invention is to provide an anti-slipping surface for a pavement, and in the particular embodiment of the invention herein described suitable means are provided for this 30 purpose and are herein shown as a metal strip member set edgewise in the paving block and adapted to project slightly above the normal wearing surface thereof. For 35 similar reasons as in the case of the anchor member, this anti-slipping member may be of generally oblong shape similar to that of the anchor member herein described, and two such members 10 are shown set in the 40 paving block of Figs. 1 and 2. The anti-slipping members may be pressed into the blocks in the same manner as the bed anchor member, as above described.

Means may be provided to cause the anti-slipping members to be engaged by the 45 material of the block to insure a more positive gripping of the anti-slipping member by the material of the block. Such means are herein shown as a series of holes 11 which, when the anti-slipping member is 50 impressed into the block when it is in a somewhat plastic condition, will be firmly engaged by the material of the block and securely lock the anti-slipping member therein.

These anti-slipping members may find 55 their most general use in the construction of roadways having relatively steep grades where it is desired to provide a purchase for draft animals or more positive engagement 60 for the wheels of motor vehicles. A combination of anti-slipping means in the surface of a block and bed anchoring means upon the underside of the block may be especially adapted for use in such instances 65 because the tendency to dislodge the blocks

from their proper relation to the roadway foundation may be relatively greater than upon substantially level roadways.

Means may be provided in the anti-slipping member for the drainage of water and 70 other accumulations therefrom the same being herein shown as a slot 12 formed in the end of the looped anti-slipping member herein shown.

In forming a completed pavement having 75 the anti-slipping means herein described, the anti-slipping members may be set into the pavement at more or less frequent intervals as required and this may be accomplished in the present instance by interspersing throughout the pavement, blocks 80 provided with anti-slipping members with ordinary smooth surfaced blocks. If preferred or necessary every block may be provided with said anti-slipping means, 85 depending upon the conditions present at each instance of use of the invention.

From the foregoing description, it will be readily understood that the present invention provides a simple and efficient means 90 for overcoming the tendency to creep which develops under heavy traffic, more particularly upon roads having such pavements as are herein referred to, and further that this invention provides an effective anti-slipping 95 means for the wearing surface of pavements.

This invention may be variously embodied or modified within the scope of the 100 subjoined claims.

I claim as my invention:

1. As a new article of manufacture, a paving block complete for handling and laying as a unit, the same comprising a malleable body with a block-reinforcing and block-positioning anchor embedded in one face thereof and projecting therefrom for engagement when laid with the block-supporting bed thereby to avoid deleterious cumulative creeping of individual blocks when 110 laid.

2. As a new article of manufacture, a paving block complete for handling and laying as a unit, the same comprising a malleable body with a block-positioning anchor partially embedded in one face thereof and projecting therefrom for engagement when laid with the block-supporting bed thereby to avoid deleterious cumulative 115 creeping of individual blocks when laid.

3. As a new article of manufacture, a paving block complete for handling and laying as a unit, the same comprising a malleable body with a block-positioning anchor partially embedded in one face thereof and projecting therefrom for engagement when laid with the block-supporting bed, said bed anchor providing extended surfaces longitudinally of the block for opposing movement 125 thereof on its bed in the direction of the 130

width of the block thereby to avoid deleterious cumulative creeping of individual blocks when laid.

4. As a new article of manufacture, a paving block complete for handling and laying as a unit, the same comprising a malleable body with a block-positioning anchor partially embedded in one face thereof and projecting therefrom for engagement when laid with the block-supporting bed, thereby to avoid deleterious cumulative creeping of individual blocks when laid, said anchor having apertures therethrough opposing separation of said anchor from said body.

15 5. A malleable paving block provided prior to laying with a bed anchor projecting from its lower surface, said bed anchor being formed of a single strip of metal bent to provide a discontinuous loop elongated 20 lengthwise of the block thereby to avoid deleterious cumulative creeping of individual blocks when laid.

6. The method of combating the creeping of bituminous paving blocks on their foundations, which comprises distributing among the blocks as laid a plurality of anchor blocks having anchoring means projecting from their lower surfaces into the upper surface of the foundation material 30 below the blocks thereby to avoid deleterious cumulative creeping of individual blocks when laid.

35 7. The method of combating the creeping of bituminous paving blocks on their foundations, which comprises distributing among the blocks as laid a plurality of anchor blocks having anchoring means partially embedded in the block and projecting from their lower surfaces into the upper 40 surface of the foundation material be-

low the blocks thereby to avoid deleterious cumulative creeping of individual blocks when laid.

8. A pavement comprising a bed surfaced with a plurality of malleable paving blocks, 45 some of said blocks having smooth bottoms and others of said blocks provided with bed anchors formed by metallic strips partially embedded in the blocks and partially in the bed, said blocks with bed anchors combating 50 bodily movement on said bed of any substantial area of said pavement.

9. A pavement comprising a bed surfaced with a plurality of malleable paving blocks, 55 said blocks of greater length than width, the body of said pavement laid with the length of the blocks extending transversely of the pavement, the edge of said pavement laid with the length of the blocks extending longitudinally of the pavement, the blocks 60 forming the edge of said pavement provided with bed anchors formed by metallic strips partially embedded in the blocks and partially in the bed, said blocks with bed anchors forming a lateral abutment or flush 65 curb to oppose lateral displacement of the blocks in the body of said pavement.

10. A pavement comprising a bed surfaced with a plurality of malleable paving blocks, some of said blocks having smooth 70 bottoms, and isolated blocks, or groups of said blocks provided with bed anchors partially embedded in the blocks and partially in the bed, said blocks with bed anchors restraining bodily movement on said bed of 75 any substantial area of said pavement.

In testimony whereof I have signed my name to this specification this thirteenth day of January, 1916.

EDWIN J. MORRISON.
